US0D1079281S

(12) **United States Design Patent** (10) **Patent No.:** **US D1,079,281 S**
(45) **Date of Patent:** **** Jun. 17, 2025**

(54) **ORAL CARE IMPLEMENT**

(71) Applicant: **Colgate-Palmolive Company**, New York, NY (US)

(72) Inventors: **Fan Gang Xie**, Yangzhou (CN); **Yanmei Ji**, Yangzhou (CN); **Wen Jin Xi**, Shanghai (CN)

(73) Assignee: **Colgate-Palmolive Company**, New York, NY (US)

(**) Term: **15 Years**

(21) Appl. No.: **29/934,638**

(22) Filed: **Mar. 27, 2024**

Related U.S. Application Data

(63) Continuation of application No. 29/829,833, filed on Mar. 8, 2022, now Pat. No. Des. 1,026,470.

(51) **LOC (15) Cl.** **04-02**

(52) **U.S. Cl.**

USPC **D4/104**

(57) **CLAIM**

The ornamental design for an oral care implement, as shown and described.

DESCRIPTION

FIG. 1 is a front perspective view of an oral care implement showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof; and,

FIG. 8 is an enlarged bottom view thereof.

The broken lines illustrate portions of the oral care implement that form no part of the claimed design.

1 Claim, 4 Drawing Sheets
